Primary Examiner — Barbara Fox(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing the new design.

The broken line showing of the two line segments, the display screen and a handset is for environmental purposes only and forms no part of the claimed design.
